COMPOSITION OF MATTER

Albert L. Flennier, Wilmington, Del., assignor to
 E. I. du Pont de Nemours & Company, Wil-
 mington, Del., a corporation of Delaware

No Drawing. Application July 30, 1938,
 Serial No. 222,217

16 Claims. (Cl. 167—22)

This invention relates to compositions of matter for use in preparing horticultural sprays and more particularly to compositions containing a finely divided water-insoluble active solid ingredient intimately mixed with an aliphatic alcohol containing from eight to fourteen carbon atoms.

In most suspensions used as horticultural sprays the finely divided, water-insoluble solid ingredient is caused to wet out by incorporating, either in the water or in the solid material, a substance which lowers the surface tension of the dispersing medium. Usually such materials have a highly detergent action which, coupled with the lowering of the surface tension, causes heavy run-off of the spray from the sprayed plant.

In view of the abnormal run-off caused by the use of such wetting agents, horticultural sprays are frequently applied in the form of simple aqueous suspensions. The preparation and application of such suspensions, particularly from materials difficultly wetted by water, requires the use of special power sprays of a capacity available to large producers only.

I have found that by intimately mixing a finely divided, water-insoluble active solid ingredient with a higher aliphatic alcohol containing at least eight carbon atoms a product is obtained which is easily wettable with water and which may be suspended therein without lowering of the surface tension. Since no lowering of the surface tension and no detergent action results from the use of aliphatic alcohols containing more than eight carbon atoms no abnormal run-off caused by such addition.

It is my belief that intimate mixing of an aliphatic alcohol containing at least eight carbon atoms with the finely divided, water-insoluble active solid ingredient causes the majority of individual particles to be wetted, at least in part, with a film of the alcohol, which film due to the presence of hydroxyl groups imparts wetting out properties to the finely divided material.

Compositions according to this invention possess the further advantage that they may be easily prepared simply by thoroly mixing the finely divided, water-insoluble active solid with an aliphatic alcohol containing more than eight carbon atoms by suitable mixing apparatus such

as a ball mill. The product so prepared retains its dry and finely divided form so that it may be marketed and transported at a minimum of cost.

In order that my invention may be more fully understood reference may be had to the following specific examples:

Example I

According to this example 99 parts of sulfur ground to 300 mesh was thoroly mixed with one part of decyl alcohol in a ball mill to give the following composition:

	Per cent	15
Sulfur—ground to 300 mesh	99	
Decyl alcohol	1	

Example II

In a like manner 99 parts of thio-diphenylamine ground to 200 mesh was thoroly mixed with one part of decyl alcohol to give the following composition:

	Per cent	25
Thio-diphenylamine—ground to 200 mesh	99	
Decyl alcohol	1	

The compositions of Examples I and II were easily dispersible in water and formed suspensions suitable by application to foliage by standard spray equipment.

In some instances it is desirable to increase the stability and dispersibility of the suspension. For this purpose a small amount of a finely divided inert solid may be incorporated in the mixture. These inerts also act as conditioning agents to prevent caking or agglomerating during storage. The following examples are illustrative:

Example III

Using a ball mill as in Example I, finely ground sulfur mixed with celite was milled with decyl alcohol to give the following composition:

	Per cent	
Sulfur—ground to 300 mesh	95	
Celite	4	
Decyl alcohol	1	50

Example IV

In a similar manner the following composition was prepared:

	Per cent
5 Tetra-methyl-thiuram-disulfide—ground to 300 mesh	80
15 Bancroft clay	19
25 Decyl alcohol	1

10 The compositions of Examples III and IV wetted out well in water and formed suspensions readily by stirring the mixture into a suitable quantity of water.

15 As some tendency toward flocculation was observed in sprays prepared from the composition of Example IV it was found desirable to include a small amount of a deflocculating agent. For this purpose a small amount of a sulfonated condensation product of naphthalene and formaldehyde was incorporated, as illustrated in the following example:

Example V

	Per cent
25 Tetra-methyl-thiuram-disulfide	80.0
30 Bancroft clay	18.8
35 Decyl alcohol	0.7
40 Sulfonated condensation product of naphthalene and formaldehyde	0.5

30 While I have specifically disclosed decyl alcohol in Examples I thru V, I prefer for economic reasons to employ technical dodecyl alcohol such as obtained by the hydrogenation of coconut oil acids. Such alcohol consists predominately of dodecyl alcohol but contains minor amounts of octyl, decyl, and tetradecyl alcohols.

35 In some cases it has been found desirable to include conditioning agents adapted to enhance the free flowing qualities of the composition. This is especially desirable with compositions containing 40 thio-diphenylamine. While for the most part inert such as celite and Bancroft clay satisfactorily perform this function, material improvement, especially in the case of thio-diphenylamine, is obtained by the inclusion of tricalcium phosphate as illustrated in the following example:

Example VI

	Per cent
50 Thio-diphenylamine	86.0-94.2
55 Technical dodecyl alcohol	0.4- 2.0
60 Tricalcium phosphate	5.0-10.0
65 Sulfonated condensation product of naphthalene and formaldehyde	0.4- 2.0

55 If desired the tricalcium phosphate may be replaced in part by other inert such as celite. Preferably, however, the tricalcium phosphate should not be less than about 1.0 per cent. A suitable composition is illustrated in the following example:

Example VII

	Per cent
65 Thio-diphenylamine	92
70 Technical dodecyl alcohol	1
75 Celite	5
80 Tricalcium phosphate	1
85 Sulfonated condensation product of naphthalene and formaldehyde	1

70 This composition has been found especially well adapted for preparing sprays used in the control of the codling moth. It disperses readily in water, forms a suspension sufficiently stable for spray purposes, is a free flowing powder easily handled in the preparation of sprays, and retains these properties during storage.

In place of tricalcium phosphate I may use other water-insoluble phosphates such as dicalcium phosphate.

75 In using certain of these alcohols, notably tetradecyl alcohol, which are solid at room temperature, it is advisable to carry out the mixing at a temperature sufficient to liquefy the alcohol. This procedure is illustrated by the following example:

Example VIII

10

According to this example 99 parts of thio-diphenylamine were mixed with one part of tetradecyl alcohol and uniformly heated to a temperature of about 50° C. This mixture while still warm was introduced into a ball mill and thoroly mixed as in Example I without further heating. The product obtained was comparable in all respects to that of Example II, no difference in the wetting-out properties being discernible.

20 It is to be understood that the foregoing examples are given by way of illustration and variations may be made not only with respect to the nature and amounts of the essential ingredients 25 as illustrated in Examples I, II and VIII, but also in respect to the nature and amounts of other ingredients which may be included to modify the properties of the mixture as illustrated in Examples III, IV, V, VI, and VII, so long as such 30 variations do not depart from the spirit of this invention, wherein wetting-out properties are imparted to a finely-divided, water-insoluble active solid ingredient by intimately mixing therewith an aliphatic alcohol containing from eight to 35 fourteen carbon atoms.

25 The alcohols useful for the purpose of this invention comprise the aliphatic alcohols containing from eight to fourteen carbon atoms, saturated or unsaturated, straight or branched 40 chain, and acyclic or alicyclic. They may be used in any amount consistent with good wetting-out properties and a dry marketable product. Too much will impart stickiness to the product and too little will give a product which is difficult to disperse, depending upon the nature of the 45 finely divided, water-insoluble active material used and the nature of such inert material as may be used. I have found from about 0.4 to about 2.0 per cent to be practical operating limits, altho it is to be understood that wetting-out 50 properties may be imparted to finely divided inert active material by the use of more or less than that amount, as long as the majority of the particles of the active material are individually wetted, at least in part, with a film of 55 an aliphatic alcohol containing from eight to fourteen carbon atoms.

55 By a proper selection of inert conditioning agents, among which may be mentioned, in addition to those given by way of illustration, such 60 inert as tripolite, kieselguhr, China clay, Bancroft clay, bentonite, kaolinite, talc, and tononite, various effects may be obtained. Thus inert may be employed to enhance the free-flowing properties of 65 the composition and to prevent caking or agglomeration during storage, to improve the dispersing properties in water, to modify the character of the spray residue or to obtain various combinations of these effects. For example, a 70 composition containing 50 per cent tetra-methyl-thiuram-disulfide, 25 per cent bentonite, 24 per cent Bancroft clay, and 1 per cent technical dodecyl alcohol illustrates a combination of these 75 effects and is particularly desirable in that it 95

provides a heavy retentive spray residue on the sprayed foliage. The inert conditioning agents may be used in any desired amounts as long as they do not mask the effect of the active ingredient by excessive dilution. Ordinarily, a minor amount, that is to say, less than the amount of active ingredient, will be found most suitable.

Further stabilization may be effected by the use of a deflocculating agent, as illustrated in Examples V, VI, and VII. Similar results may be obtained with other non-detergent dispersing agents such as goulac, glue, gelatin, and casein. Such materials as exercise appreciable detergent action or lowering of the surface tension are undesirable for this purpose.

According to this invention, aliphatic alcohols are useful for imparting wetting-out properties to a large variety of water-insoluble active solids and are particularly useful in this respect in admixture with active materials such as sulfur, thiadiphenylamines and thiuram sulfides, which not only are insoluble in water but also exhibit pronounced hydrophobic properties. Wetting-out and dispersing properties may be imparted to any water-insoluble solid capable of being wetted by an aliphatic alcohol containing from eight to fourteen carbon atoms.

As previously indicated, the wetting-out property imparted to the finely divided, water-insoluble active solid by an aliphatic alcohol containing from eight to fourteen carbon atoms is probably due to the formation of a film of the alcohol on or about the individual particles and finely divided active solid. As the fine state of subdivision of the active material creates a surface which is inordinately large with respect to the mass of the active material such a film would necessarily be of the order of a mono molecular film. The presence of such a film, tho difficult to establish as a fact, is consistent with generally accepted views with respect to analogous phenomena.

In view of the fact, however, that the presence of such a film can be proved only with difficulty, and in view of the fact that reputable authorities may disagree as to the existence of such a film, I do not intend that my invention be limited by the particular theory which I have advanced or by any other particular theory. Consequently, reference to the presence of the aforementioned film on or about the individual particles of the finely divided active solid is intended only as a measure of the thoroughness with which the alcohol and the finely divided active solid are intimately mixed together.

This application is a continuation-in-part of my copending application Serial No. 151,846, filed July 3, 1937.

60 I claim:

1. A composition of matter in the form of a dispersible free-flowing powder for use in preparing horticultural sprays comprising a finely divided, water-insoluble active solid intimately mixed with an aliphatic alcohol containing from eight to fourteen carbon atoms.

2. A composition of matter in the form of a dispersible free-flowing powder for use in preparing horticultural sprays comprising a finely divided, water-insoluble active solid and a finely divided inert solid intimately mixed with an aliphatic alcohol containing from eight to fourteen carbon atoms.

3. A composition of matter in the form of a dispersible free-flowing powder for use in pre-

paring horticultural sprays comprising finely divided sulfur intimately mixed with an aliphatic alcohol containing from eight to fourteen carbon atoms.

4. A composition of matter in the form of a dispersible free-flowing powder for use in preparing horticultural sprays comprising finely divided sulfur and a finely divided inert solid intimately mixed with an aliphatic alcohol containing from eight to fourteen carbon atoms.

5. A composition of matter in the form of a dispersible free-flowing powder for use in preparing horticultural sprays comprising finely divided thiadiphenylamine intimately mixed with an aliphatic alcohol containing from eight to fourteen carbon atoms.

6. A composition of matter in the form of a dispersible free-flowing powder for use in preparing horticultural sprays comprising finely divided thiadiphenylamine and a finely divided inert solid intimately mixed with an aliphatic alcohol containing from eight to fourteen carbon atoms.

7. A composition of matter in the form of a dispersible free-flowing powder for use in preparing horticultural sprays comprising finely divided tetra-methyl-thiuram disulfide intimately mixed with an aliphatic alcohol containing from eight to fourteen carbon atoms.

8. A composition of matter in the form of a dispersible free-flowing powder for use in preparing horticultural sprays comprising finely divided tetra-methyl-thiuram-disulfide and a finely divided inert solid intimately mixed with an aliphatic alcohol containing from eight to fourteen carbon atoms.

9. A composition of matter in the form of a dispersible free-flowing powder for use in preparing horticultural sprays consisting essentially of finely divided sulfur intimately mixed with about 0.4 to about 2 per cent of technical dodecyl alcohol.

10. A composition of matter in the form of a dispersible free-flowing powder for use in preparing horticultural sprays consisting essentially of finely divided sulfur and a minor amount of a finely divided inert solid intimately mixed with about 0.4 to about 2 per cent of technical dodecyl alcohol.

11. A composition of matter in the form of a dispersible free-flowing powder for use in preparing horticultural sprays consisting essentially of finely divided tetra-methyl-thiuram-disulfide intimately mixed with about 0.4 to about 2 per cent of technical dodecyl alcohol.

12. A composition of matter in the form of a dispersible free-flowing powder for use in preparing horticultural sprays consisting essentially of finely divided tetra-methyl-thiuram-disulfide and a minor amount of a finely divided inert solid intimately mixed with about 0.4 to about 2 per cent of technical dodecyl alcohol.

13. A composition of matter in the form of a dispersible free-flowing powder for use in preparing horticultural sprays consisting essentially of finely divided thiadiphenylamine and a minor amount of a finely divided inert water-insoluble solid intimately mixed with about 0.4 to about 2 per cent of technical dodecyl alcohol.

14. A composition of matter in the form of a dispersible free-flowing powder for use in preparing horticultural sprays consisting essentially of finely divided thiadiphenylamine and a minor amount of a finely divided inert water-insoluble solid comprising calcium phosphate intimately mixed with about 0.4 to about 2 per cent of an

aliphatic alcohol containing from eight to fourteen carbon atoms.

15. A composition of matter in the form of a dispersible free-flowing powder for use in preparing horticultural sprays containing in intimate admixture about five to ten parts of an inert water-insoluble solid of which at least about one part is tricalcium phosphate, about 0.4 to 2 parts of an aliphatic alcohol containing from eight to 10 fourteen carbon atoms, about 0.4 to 2 parts of a non-detergent deflocculating agent and thio-diphenylamine to make about 100 parts.

16. A composition of matter in the form of a dispersible free-flowing powder for use in preparing horticultural sprays having essentially the following composition:

	Per cent	5
Thio-diphenylamine	92	
Technical dodecyl alcohol	1	
Celite	5	
Tricalcium phosphate	1	
Sulfonated condensation product of naphthalene and formaldehyde	10	

ALBERT L. FLENNER.
